CIGARETTE ALIGNING DEVICE

Elberon D. Smith, Brooklyn, N. Y., assignor to
American Machine & Foundry Company, a
corporation of New Jersey

Application February 1, 1933. Serial No. 654,699

5 Claims. (Cl. 131—39)

This invention relates to improved cigarette collectors or "catchers" for continuous-rod cigarette machines, its main object being to collect cork-tipped or similar cigarettes issuing from the 5 cut-off of the cigarette machine at high speed, in two individual rows with the tips of each row all pointing in the same direction.

To accomplish these objects, the cigarettes are delivered by the cut-off to a pair of fast-running 10 parallel transfer belts which grip the cigarettes between them and thus propel the same, in the received position but separated longitudinally owing to the greater speed of the transfer belts, into axial compartments of a pocketed conveyor in 15 which the cigarettes are automatically aligned into two separate rows with the tips pointing in opposite directions. The aforesaid pocketed conveyor has an even number of compartments and every second compartment is provided with a 20 transverse partition for positioning the cigarettes on the conveyor. The cigarettes entering the conveyor are delivered to each of the compartments, the alignment of the thus delivered cigarettes remaining the same, until the conveyor has 25 propelled them across a table onto a slow moving belt which is mounted at right-angles in respect to the pocketed conveyor. The cigarettes thus deposited onto the belt are moved axially inward in their compartments until arrested by the afore- 30 said division walls or by the end walls of the conveyor, and, after leaving the belt, the cigarette from each compartment is discharged upon a delivery belt. In this manner, the cigarettes discharged from the divided compartments form one 35 row, and those discharged from the undivided compartments form a second row upon the delivery belt.

If plain cigarettes are to be made by the cigarette machine, the partitions in the alternate compartments may be omitted, so that cigarettes are delivered upon the delivery belt in a single 40 row.

All the motions are derived from the main-shaft of the machine, thus the speed of the pocketed conveyor and the propelling belts are 45 in synchronism with that of the cut-off so that once the pocketed conveyor is set correctly, its compartments will always register with the incoming cigarettes.

In the accompanying drawings which form a 50 part of this specification, and in which like characters of reference indicate the same or like parts:

Fig. 1 is a top view of the improved cigarette 55 collector;

Fig. 2 is a side elevation of the same; and
Fig. 3 is an end view taken on line 3—3 of
Fig. 2.

In carrying the invention into effect there is provided an endless conveyor having an even 60 number of compartments said compartments extending transversely of said conveyor and alternate compartments having a transverse wall at one end and the other compartments having a transverse partition between their ends, a table 65 underlying said conveyor means for delivering tipped cigarettes endwise on said table into each of said compartments whereby the cigarettes are pushed sidewise along said table, and an endless travelling belt on said table moving 70 transversely of said conveyor to engage and move the cigarettes in each compartment endwise against said end walls and partitions respectively, whereby the cigarettes are aligned in two 75 separate rows with the tips of the cigarettes in one row all pointing in one direction and the tips of the cigarettes in the other row all pointing in the other direction. In the best forms of construction contemplated the belt on the table is arranged at right angles to the conveyor. 80 These various means and parts may be widely varied in construction for the particular device selected to illustrate the invention is but one of many possible concrete embodiments of the same. The invention, therefore, is not to be restricted to the specific construction shown and described.

To the bed 10 of the cigarette machine are fastened a set of brackets 11 and a set of brackets 12. The brackets 11 support a driven shaft 96 13 carrying a pulley 14 which drives an endless belt 15 running over an idler pulley 16 loosely mounted on a shaft 17 supported by the brackets 12. The conveyor 15 carries a number of spaced angular compartments 18, every alternate compartment of which is subdivided longitudinally by a transverse partition.

The bed 10 also carries brackets (not shown) which support a table 19. The table 19 is provided with a transverse recess 20, which receives 100 a belt 21 disposed therein in alignment with the top of table 19. The belt 21 runs over pulleys 22 and 23 on shafts 24 and 25 respectively. The driven shaft 13 carries a gear 26 which meshes with a gear 27 fastened to the shaft 24, thus 105 driving the pulley 22. The shafts 24 and 25 are supported by brackets 28 and 29 carried by the bed 10.

The cigarettes "C" issuing from the cut-off enter between endless transfer belts 30 and 31. 110

The upper transfer belt 30 runs over pulleys 32 and 33 on studs 34 and 35, which are carried by a bracket 36 resting on the bed 10. The stud 34 also carries a spur gear 37. The lower transfer belt 31 runs over a pulley 38 mounted on a stud 39, over pulley 40 on a stud 41, over a drive pulley 42 on shaft 43, and over a tightener pulley 44 on a stud 45. The shaft 43 which is driven by suitable means (not shown), carries a spur gear 46 which drives an intermediate gear 47, thus driving the gear 37 on stud 34.

The cigarettes are delivered endwise on the table 19 into each compartment of the conveyor 15 and pushed laterally over the table 19 onto the belt 21 by the vertical side wall of the next compartment. In this manner the cigarettes, while being pushed across the belt 21, are moved axially inward by the belt until they stop against the partitions 48, or one of the end walls 49, according to whether the cigarette happens to be in an undivided or in a divided compartment. Since belt 21 runs at a slow speed, it permits the cigarettes to stop gently against the aforesaid partitions, thus eliminating the possibility of damaging the ends of the cigarettes.

The conveyor 15 and the transfer belts 30 and 31 are so timed with reference to the cut-off that a cigarette is fed into each compartment of the conveyor as the compartment registers with the transfer belts, therefore the cigarettes proceeding from the cut-off are alternately placed into a divided and into an undivided compartment, and all cigarettes with the cork-tip pointing in one direction are lined up against the partitions 48 and all those pointing the other way, against the end walls 49. Thus the cigarettes "C" are discharged onto a delivery belt 50, running over a pulley 51 on shaft 52 supported by the brackets 11, on which they form two separate rows.

40. What is claimed is:

1. In a cigarette collector for tipped cigarettes, the combination with an endless conveyor provided with an even number of open compartments, said compartments extending transversely of said conveyor, and consisting of alternate compartments having a transverse wall at one end and other compartments having a transverse partition between their ends, a table underlying said conveyor, means for delivering tipped cigarettes endwise on said table into each of said compartments, whereby the cigarettes are pushed sidewise along said table, and an endless travelling belt on said table moving transversely of said conveyor to engage and move the cigarettes in each compartment endwise against said end walls and partitions respectively, whereby the cigarettes are aligned in two separate rows with the tips of the cigarettes in one row all pointing in one direction and the tips of the cigarettes in the other row all pointing in the other direction.

2. In a cigarette collector for tipped cigarettes, the combination with an endless conveyor provided with an even number of open compartments, said compartments extending transversely of said conveyor, and consisting of alternate compartments having a transverse wall at one end and other compartments having a transverse partition between their ends, a table underlying said conveyor, means for delivering tipped cigarettes endwise on said table into each of said compartments, whereby the cigarettes are pushed sidewise along said table, and an endless travel-

ling belt on said table moving transversely of said conveyor to engage and move the cigarettes in each compartment endwise against said end walls and partitions respectively, whereby the cigarettes are aligned in two separate rows with the tips of the cigarettes in one row all pointing in one direction and the tips of the cigarettes in the other row all pointing in the other direction, said conveyor including an endless belt on which said compartments are fixed.

3. In a cigarette collector for tipped cigarettes, the combination with an endless conveyor provided with an even number of open compartments, said compartments extending transversely of said conveyor, and consisting of alternate compartments having a transverse wall at one end and other compartments having a transverse partition between their ends, a table underlying said conveyor, means for delivering tipped cigarettes endwise on said table into each of said compartments, whereby the cigarettes are pushed sidewise along said table, and an endless travelling belt on said table moving transversely of said conveyor to engage and move the cigarettes in each compartment endwise against said end walls and partitions respectively, whereby the cigarettes are aligned in two separate rows with the tips of the cigarettes in one row all pointing in one direction and the tips of the cigarettes in the other row all pointing in the other direction, said belt being arranged at right angles to said conveyor.

4. In a cigarette collector for tipped cigarettes, the combination with an endless conveyor provided with an even number of open compartments, said compartments extending transversely of said conveyor, and consisting of alternate compartments having a transverse wall at one end and other compartments having a transverse partition between their ends, a table underlying said conveyor, means for delivering tipped cigarettes endwise on said table into each of said compartments, whereby the cigarettes are pushed sidewise along said table, and an endless travelling belt on said table moving transversely of said conveyor to engage and move the cigarettes in each compartment endwise against said end walls and partitions respectively, whereby the cigarettes are aligned in two separate rows with the tips of the cigarettes in one row all pointing in one direction and the tips of the cigarettes in the other row all pointing in the other direction, said belt being arranged at right angles to said conveyor.

5. In a cigarette collector, the combination with an endless conveyor provided with open compartments, said compartments extending transversely of said conveyor, a table underlying said conveyor, means for delivering cigarettes endwise on said table into each of said compartments, whereby the cigarettes are pushed sidewise along said table, an endless travelling belt arranged at right angles to said conveyor to engage and align the cigarettes in said compartments, and a delivery belt arranged to receive the aligned cigarettes as they are pushed from said table by the compartments of said conveyor.

ELBERON D. SMITH.
